DESIGN FOR A SOAP DISH

Elizabeth G. Welles, Lexington, Va.

Application November 24, 1937, Serial No. 73,176

Term of patent 7 years

To all whom it may concern:

Be it known that I, Elizabeth G. Welles, a citizen of the United States, residing in the city of Lexington, in the county of Rockbridge, in the State of Virginia, have invented a new, original, and ornamental Design for Soap Dishes, of which the following is a specification, reference being had to the accompanying drawing, forming part thereof.

In the drawing:

Fig. 1 is a side elevational view of a soap dish showing my new design.

Fig. 2 is a top plan view of a soap dish.

I claim:

The ornamental design for a soap dish, as shown.

ELIZABETH G. WELLES.
